LAUNDRY CLASSIFYING TABLE

Elmer F. Cons and Clarence F. Cons,
Kansas City, Mo.

Application October 2, 1939, Serial No. 297,444

11 Claims. (Cl. 211—10)

This invention relates to improvements in laundry classifying tables and particularly to a table of this character wherein certain parts are retractable to facilitate convenient and rapid classification.

It has become common practice with the various laundries to wash the soiled clothes in nets. These nets comprise an open-end bag made of a strong cotton mesh material which will permit a free movement of the wash water to and from the bag. The average bundle of clothes received from the customers is composed of pieces of different colors, materials and articles that require special treatment, and it is therefore necessary to classify the bundles so that similar pieces of clothing are placed in the same net. In most instances, it is found expedient to divide the original bundle into several lots to be placed in different nets for the washing operation. Each net of this particular bundle may now be washed with corresponding articles of other bundles, and since all the nets of a certain bundle contain like identification means, they can be reassembled, after the washing and other necessary operations, for delivery.

The speed and accuracy of this classification operation, that is the separation of the clothing of the bundle into the various net lots, depends to a large degree upon the relation of various parts of the table to the operator during the classifying operation. It is the principal object of the present invention to provide a laundry classifying table wherein the bundle supporting platform is movable to and from the operative position relative to the series of bins.

Another object of the invention is the provision of a laundry classifying table comprising a frame-work having a substantially U-shaped top on which is mounted a series of bins and a retractable platform adapted to be moved to and from a position in the bight, formed by the U-shaped top, whereby the laundry bundle may be supported therein, also when the platform is retracted the operator may stand therein during the placing of the contents of the various bins in their respective net bags.

A further object of this invention is the provision of a side wall hingedly carried by the bundle supporting platform to form a front wall for the bundle compartment and to be retracted with the platform.

Other objects are economy and simplicity of construction; ease and speed of operation; and

adjustability of the parts to accommodate the various types of bundles of clothing.

Reference will now be had to the drawings wherein:

5 Figure 1 is a plan view, partly broken away, of a laundry classifying table embodying this invention.

Fig. 2 is a front elevation, with parts broken away, of the table shown in Fig. 1.

10 Fig. 3 is a vertical central section taken on line III—III of Fig. 1.

Fig. 4 is an enlarged fragmentary sectional view taken on line IV—IV of Fig. 3.

15 Fig. 5 is an enlarged fragmentary sectional view taken on line V—V of Fig. 3.

Fig. 6 is a sectional view taken on line VI—VI of Fig. 5.

20 Fig. 7 is a fragmentary sectional view of the rear end of one of the partitions together with its associated parts.

Fig. 8 is a fragmentary view of the front portion of one of the partitions with its associated parts.

25 Fig. 9 is a fragmentary elevation of a portion of the wall member and certain associated parts; and,

Fig. 10 is a side elevation of the parts shown in Fig. 9.

Throughout the several views, like reference characters designate similar parts and the numeral 10 is a frame supporting a table top 12. Frame 10 is preferably made of fabricated steel and consists of front legs 14 and rear legs 16, joined together adjacent their lower extremities 35 by horizontal bars 18 and 20, and at their top extremities by horizontally disposed members 22 and 26. Extending from the front legs 14 to rear legs 16 intermediate cross members 20 and 26, is a pair of spaced apart braces 28 which 40 carries a U-shaped angle iron 30.

Table top 12 is substantially U-shaped, as clearly shown in Fig. 1, and serves as a bottom for the series of bins 32. The rear ends of the bins are formed by the vertically disposed arcuate sheet 33 carried by table top 12, and the side walls are produced by the radially disposed partition members 34, which are adapted to be adjusted transversely to vary the relative size of the various bins. It will be noted that the bins are open at the front to receive the clothing, as hereinafter described.

Referring to Figs. 3, 7 and 8, it is apparent that the partition 34 is provided on its rear and bottom sides with a metal edging 36, which is secured thereto by means of screws 38. Each

partition 34 is notched out at 40 and the edging 36 extends to the front edge of the partition and is provided with an upstanding pin 42. A pin 44, extending downwardly from edging 36 adjacent the rear edge of the partition, extends through hole 46 formed in top 12; also, machine screw 48 passes through opening 50 in sheet 33 and is threaded into edging 36, while screw 52 passes through opening 54 formed through top 12 and engages in a threaded hole 56 formed in edging 36.

As clearly shown in Fig. 1, there is a series of holes 46 and a series of holes 54, also openings 50 in sheet 33 are in a uniform series. Openings 50 and holes 46 and 54 are so related that the partitions may be easily and quickly adjusted to any desired position to vary the size of the various bins. When classifying the ordinary wash bundle, it is desirable to have some small bins and some larger bins to accommodate the different size lots for the various nets.

An angle iron 58 secured to the lower side of top 12 extends around the inner arcuate edge thereof and is positioned directly above angle iron 30. An arcuate plate 60 joins together angles 30 and 58 to form a wall for the bundle receiving compartment 62. The outer edge of top 12 is provided with a reinforcing angle iron 64 which also serves as an anchoring means for sheet 33. Bracket 66 secured to member 26 and angle iron 30 serves to support the parts against weaving.

The extended forward portion 68 of table top 12, serves as a desk for the operator, and it is apparent that drawers, bins, etc., might be included beneath this table to receive equipment, etc., incident to the carrying on the classification operation.

A shelf 70 supported on bracket 72 carried by leg 14 may be used to support the net bag during its closing and tagging operation. Due to the shape of top 12 and frame 10, a horizontally disposed bight 73 is formed throughout the vertical height of the table. This bight is normally open to the front of the table and is adapted to be closed by means, hereinafter described.

The bundle receiving compartment 62 is provided with a bundle supporting platform or bottom 74 that is movable to and from the operative position. This platform is positioned below the plane of top 12 so that the bundle of clothes resting thereon will not interfere with the operator's free access to the various bins during the classification operation.

Platform 74 is supported for oscillatory movement on a pair of arms 76 which are pivotally mounted intermediate their ends at 75 to frame bars 20 and to platform 74, by means of pins 77, which is secured to bracket 78, which in turn is affixed to the underside of the platform adjacent its rear portion. The forward portion of the platform is provided at its opposite edges with bracket 80 which carries a roller 82 adapted to engage the channel track 84 which is securely mounted on frame 10. A weight compensating spring 86 is secured by its one end to rear leg 16 and at its other end to the lower end of arm 76 through holes 88. These holes are spaced at different distances from the pivotal point 75 of arm 76 so that by attaching the spring in different holes, the tension may be varied to obtain proper balancing of the particular platform.

The sectional view (Fig. 4) best shows the pivotal connection of arm 76 with bar 20. A thimble formed by sleeve 90 is mounted in an opening

94 formed through arm 76. Bolt 96 passing through hole 98 formed through channel bar 20, passes through sleeve 90 and is provided with a nut 100 by means of which the parts are secured 5 together.

It will be noted that platform 74 practically fills the bight and when in the operative position, extends beneath the angle iron 30.

Track 84 is rearwardly and downwardly inclined and has an upwardly extending arcuate portion 102 at its front end. Pivotally attached by pins 104 to the front edge of platform 74, is a wall member 106 having securely attached brackets 108, carrying guide rollers 110, adapted to engage track 84 and extend into the arcuate portion 102 thereof. An opening 112 formed through wall member 106 produces a hand-grip by means of which the platform and side wall may be manually moved to the desired position.

Referring to Fig. 3, solid lines, the platform 74 and side wall 106 are shown in the position in the bight to receive a bundle of clothes to be sorted. The dotted lines indicate the position of these parts when the platform is retracted to 25 the inoperative position.

A cross member 114 joining the rear legs 16 carries a resilient bumper 116 which stops the downward movement of the platform. It will be noted that the hand-grip of wall member 106, extends into the bight when the parts are retracted so that it is accessible to the operator to again move the parts to the operative position.

The platform and wall member are so constructed and mounted that they will automatically retain their position when in the operative and inoperative positions.

A stop 118 carried by wall member 106, limits the angled relation between platform 74 and wall member 106.

In the operation of this machine, the operator first moves the platform 74 and side wall 106 to the raised position and places a bundle of soiled clothing therein. Each article of the bundle is placed in its proper bin—the operator then engages the hand-grip and moves the parts to the retracted position, shown in dotted lines of Fig. 3. The operator enters the bight, places a net bag over two of the adjacent pins 42, and drags the contents of the bin therebetween into the net. This operation is repeated until the contents of all the bins are properly positioned in their respective nets. Each net is closed and tagged for identification. They are now ready for the wash, and when the washing is completed, they are re-assembled by referring to the identifying tags, for delivery to the customer.

When the operator is standing in the bight, he has ready access to all the bins and can view all portions of each bin, thus making it possible to detect any articles left therein.

In actual practice, the use of this table has greatly increased the speed of classifying and has also reduced mistakes to a minimum.

Since many modifications might be made in the construction of this device without departing from the spirit of the invention, it is desired to be limited only by the scope of the appended claims.

Having thus described the invention, what is claimed as new and desired to be secured by Letters Patent is:

1. A laundry classification table comprising a frame having a bight formed therein to extend vertically through said table; a series of bins carried on said frame about said bight; and a bundle

supporting platform adapted to be moved to and from a position in said bight to permit access of the operator to said bight.

2. A laundry classifying table comprising a frame having a horizontally disposed bight formed therein; a series of open bins carried by said frame about said bight; and a bundle supporting platform carried at its rear end by a pair of spaced apart arms pivoted to said frame and at its front end by a pair of rollers engaging tracks secured to said frame whereby it is movable to and from a position in said bight.

3. A laundry classifying table comprising a frame including a top member having a bight formed in one side portion thereof; a series of bins formed about said bight on said top member; a platform movably carried by said frame whereby it is movable to and from a horizontal position in said bight to permit access of the operator to said bight.

4. A laundry classifying table comprising a frame having a top member with a bight formed in one of its side portions; partitions adjustably carried by said frame to form open bins of predetermined size at the top portion of said frame; a movable bundle carrying platform carried by said frame, movable to and from a position in said bight.

5. A laundry classifying table comprising a frame having a bight formed therein; a series of bins carried by said frame about said bight; stationary tracks carried by said frame; arms pivoted to said frame; and a platform supported at its rear portion by said arms and having rollers adjacent its front portion to operatively engage said stationary tracks whereby it is movable to and from a position in said bight.

6. A laundry classifying table comprising a frame having a bight formed therein; a series of bins carried by said frame about said bight; a platform supported at its rear portion by arms pivoted to said frame and its front portion by rollers mounted in stationary tracks whereby it is movable to and from a position in said bight; and a wall member hinged to said platform and supported at its free edge by rollers mounted in said track.

7. A laundry classifying table comprising a frame having a horizontally disposed bight formed therein; a series of radially disposed bins

carried by said frame about said bight; stationary tracks carried by said frame; arms pivoted to said frame; and a platform having rollers at its front portion to operatively engage said stationary tracks and being connected to the free ends of said pivoted arms whereby said platform is movable to and from a position in said bight.

8. A laundry classifying table comprising a frame having a bight formed therein; a bundle supporting platform carried by said frame adapted to be moved to and from a position in said bight; and a side wall hinged to the front edge of said platform and slidably carried in guide tracks for movement to and from the operative position as said platform is moved.

9. A laundry classifying table comprising a frame having a bight in one of its edge portions and having a series of bins; a bundle supporting platform rotatably carried adjacent its rear portion by a pair of arms pivoted below said platform to said frame and pivoted at its front portion by means of trunnions mounted in stationary tracks carried by said frame whereby said platform is movable to and from a position in said bight and a side wall pivoted to said platform and slidably mounted in said stationary track.

10. A laundry classifying table comprising a frame having a horizontal bight extending throughout its vertical height, a platform slidably mounted at its front portion in stationary tracks carried by said frame and rotatably mounted adjacent its rear edge on oscillatable arms pivotally carried by said frame whereby said platform is movable to and from a position in said bight; and resilient means operable to maintain said platform in the operative position in said bight.

11. A laundry classifying table comprising a frame having a bight in one of its edge portions and having a series of bins at its top portion, positioned above and about said bight; a platform rotatably and slidably carried adjacent its front portion by a pair of stationary tracks and rotatably mounted adjacent its rear portion on a pair of arms pivoted to said frame for movement to and from a position in said bight whereby the operator may have access to said bight.
